(57) **CLAIM**

The ornamental design for a football display holder for a cord, as shown and described.

DESCRIPTION

FIG. 1 is a perspective view of a football display holder for a cord of the present invention;

FIG. 2 is a front elevational view of the football display holder for a cord of FIG. 1;

FIG. 3 is a rear elevational view of the football display holder for a cord of FIG. 1;

FIG. 4 is a left side elevational view of the football display holder for a cord of FIG. 1;

FIG. 5 is a right side elevational view of the football display holder for a cord of FIG. 1;

FIG. 6 is a top elevational view of the football display holder for a cord of FIG. 1;

FIG. 7 is a bottom elevational view of the football display holder for a cord of FIG. 1; and,

FIG. 8 is a rear perspective view of the football display holder for a cord of FIG. 1.

Trademark Office on Sep. 20, 2011 for U.S. Appl. No. 29/394,593,
filed Jun. 18, 2011 (First Named Inventor—Dunn) (7 pages).

Entered July 18, 2011 (First Named Inventor - Dunn) (7 pages).
Supplemental Notice of Allowability entered by the U.S. Patent and
Trademark Office on Oct. 12, 2011 for U.S. Appl. No. 29/394,593,
21 JUN 19, 2011 (First Name Inventor - Dunn) (2 pages).

filed Jun. 18, 2011 (First Named Inventor—Dunn) (2 pages). Issue Notification entered by the U.S. Patent and Trademark Office on Jan. 11, 2012 for U.S. Appl. No. 29/394,593, filed Jun. 18, 2011 (First Named Inventor—Dunn) (1 page).

Specification, Claims, and Drawings entered by the U.S. Patent and Trademark Office on Jun. 18, 2011 for U.S. Appl. No. 29/394,594, filed Jun. 18, 2011 (First Named Inventor—Dunn) (7 pages).

Notice of Allowance and Fees Due entered by the U.S. Patent and Trademark Office on Sep. 23, 2011 for U.S. Appl. No. 29/394,594, filed Jun. 18, 2011 (First Named Inventor—Dunn) (7 pages).
Supplemental Notice of Allowability entered by the U.S. Patent and

Supplemental Notice of Allowability entered by the U.S. Patent and Trademark Office on Nov. 29, 2011 for U.S. Appl. No. 29/394,594, filed Jun. 18, 2011 (First Named Inventor—Dunn) (2 pages).
Issue Notification entered by the U.S. Patent and Trademark Office

on Jan. 11, 2012 for U.S. Appl. No. 29/394,594, filed Jun. 18, 2011 (First Named Inventor—Dunn) (1 page).
Specification, Claims, and Drawings entered by the U.S. Patent and Trademark Office on Jun. 18, 2011 for U.S. Appl. No. 29/394,595.

Trademark Office on Jun. 18, 2011 for U.S. Appl. No. 29/394,595, filed Jun. 18, 2011 (First Named Inventor—Dunn) (12 pages). Notice of Allowance and Fees Due entered by the U.S. Patent and Trademark Office on Sep. 23, 2011 for U.S. Appl. No. 29/394,595,

filed Jun. 18, 2011 (First Named Inventor—Dunn) (7 pages).

Supplemental Notice of Allowability entered by the U.S. Patent and Trademark Office on Oct. 26, 2011 for U.S. Appl. No. 29/394,595, filed Jun. 18, 2011 (First Named Inventor—Dunn) (2 pages).
Issue Notification entered by the U.S. Patent and Trademark Office on Jan. 11, 2012 for U.S. Appl. No. 29/394,595, filed Jun. 18, 2011 (First Named Inventor—Dunn) (1 page).
Specification, Claims, and Drawings entered by the U.S. Patent and Trademark Office on Jun. 18, 2011 for U.S. Appl. No. 29/394,596, filed Jun. 18, 2011 (First Named Inventor—Dunn) (23 pages).
Requirement for Restriction/Election entered by the U.S. Patent and Trademark Office on Sep. 29, 2011 for U.S. Appl. No. 29/394,596, filed Jun. 18, 2011 (First Named Inventor—Dunn) (5 pages).
Response to Restriction Requirement entered by the U.S. Patent and Trademark Office on Nov. 4, 2011 for U.S. Appl. No. 29/394,596, filed Jun. 18, 2011 (First Named Inventor—Dunn) (2 pages).
Notice of Allowance and Fees Due entered by the U.S. Patent and Trademark Office on Dec. 13, 2011 for U.S. Appl. No. 29/394,596, filed Jun. 18, 2011 (First Named Inventor—Dunn) (9 pages).
Specification, Claims, and Drawings entered by the U.S. Patent and Trademark Office on Jun. 18, 2011 for U.S. Appl. No. 29/394,597, filed Jun. 18, 2011 (First Named Inventor—Dunn) (29 pages).
Requirement for Restriction/Election entered by the U.S. Patent and Trademark Office on Sep. 29, 2011 for U.S. Appl. No. 29/394,597, filed Jun. 18, 2011 (First Named Inventor—Dunn) (5 pages).
Response to Restriction Requirement entered by the U.S. Patent and Trademark Office on Nov. 29, 2011 for U.S. Appl. No. 29/394,597, filed Jun. 18, 2011 (First Named Inventor—Dunn) (2 pages).
Notice of Allowance and Fees Due entered by the U.S. Patent and Trademark Office on Jan. 5, 2012 for U.S. Appl. No. 29/394,597, filed Jun. 18, 2011 (First Named Inventor—Dunn) (8 pages).
Specification, Claims, and Drawings entered by the U.S. Patent and Trademark Office on Jun. 18, 2011 for U.S. Appl. No. 29/394,598, filed Jun. 18, 2011 (First Named Inventor—Dunn) (7 pages).
Notice of Allowance and Fees Due entered by the U.S. Patent and Trademark Office on Sep. 19, 2011 for U.S. Appl. No. 29/394,598, filed Jun. 18, 2011 (First Named Inventor—Dunn) (7 pages).
Supplemental Notice of Allowability entered by the U.S. Patent and Trademark Office on Oct. 25, 2011 for U.S. Appl. No. 29/394,598, filed Jun. 18, 2011 (First Named Inventor—Dunn) (2 pages).
Issue Notification entered by the U.S. Patent and Trademark Office on Jan. 4, 2012 for U.S. Appl. No. 29/394,598, filed Jun. 18, 2011 (First Named Inventor—Dunn) (1 page).
Specification, Claims, and Drawings entered by the U.S. Patent and Trademark Office on Jun. 18, 2011 for U.S. Appl. No. 29/394,599, filed Jun. 18, 2011 (First Named Inventor—Dunn) (8 pages).
Notice of Allowance and Fees Due entered by the U.S. Patent and Trademark Office on Sep. 23, 2011 for U.S. Appl. No. 29/394,599, filed Jun. 18, 2011 (First Named Inventor—Dunn) (7 pages).
Supplemental Notice of Allowability entered by the U.S. Patent and Trademark Office on Oct. 26, 2011 for U.S. Appl. No. 29/394,599, filed Jun. 18, 2011 (First Named Inventor—Dunn) (2 pages).
Issue Notification entered by the U.S. Patent and Trademark Office on Jan. 11, 2012 for U.S. Appl. No. 29/394,599, filed Jun. 18, 2011 (First Named Inventor—Dunn) (1 page).
Specification, Claims, and Drawings entered by the U.S. Patent and Trademark Office on Jun. 18, 2011 for U.S. Appl. No. 29/394,600, filed Jun. 18, 2011 (First Named Inventor—Dunn) (12 pages).
Requirement for Restriction/Election entered by the U.S. Patent and Trademark Office on Sep. 29, 2011 for U.S. Appl. No. 29/394,600, filed Jun. 18, 2011 (First Named Inventor—Dunn) (5 pages).
Response to Restriction Requirement entered by the U.S. Patent and Trademark Office on Nov. 17, 2011 for U.S. Appl. No. 29/394,600, filed Jun. 18, 2011 (First Named Inventor—Dunn) (2 pages).
Notice of Allowance and Fees Due entered by the U.S. Patent and Trademark Office on Dec. 12, 2011 for U.S. Appl. No. 29/394,600, filed Jun. 18, 2011 (First Named Inventor—Dunn) (9 pages).
Amendment and Response to Notice of Allowability entered by the U.S. Patent and Trademark Office on Feb. 2, 2012 for U.S. Appl. No. 29/394,600, filed Jun. 18, 2011 (First Named Inventor—Dunn) (9 pages).
Issue Notification entered by the U.S. Patent and Trademark Office on Feb. 29, 2012 for U.S. Appl. No. 29/394,600, filed Jun. 18, 2011 (First Named Inventor—Dunn) (1 page).

Specification, Claims, and Drawings entered by the U.S. Patent and Trademark Office on Jan. 19, 2012 for U.S. Appl. No. 29/411,283, filed Jan. 19, 2012 (First Named Inventor—Dunn) (7 pages).
Specification, Claims, and Drawings entered by the U.S. Patent and Trademark Office on Jan. 19, 2012 for U.S. Appl. No. 29/411,284, filed Jan. 19, 2012 (First Named Inventor—Dunn) (7 pages).
Specification, Claims, and Drawings entered by the U.S. Patent and Trademark Office on Jan. 19, 2012 for U.S. Appl. No. 29/411,285, filed Jan. 19, 2012 (First Named Inventor—Dunn) (7 pages).
Notice of Allowance entered by the U.S. Patent and Trademark Office on Apr. 9, 2012 for U.S. Appl. No. 29/411,285, filed Jan. 19, 2012 (First Named Inventor—Dunn) (7 pages).
Specification, Claims, and Drawings entered by the U.S. Patent and Trademark Office on Jan. 19, 2012 for U.S. Appl. No. 29/411,288, filed Jan. 19, 2012 (First Named Inventor—Dunn) (7 pages).
Notice of Allowance and Fees Due entered by the U.S. Patent and Trademark Office on Mar. 2, 2012 for U.S. Appl. No. 29/411,286, filed Jan. 19, 2012 (First Named Inventor—Dunn) (7 pages).
Specification, Claims, and Drawings entered by the U.S. Patent and Trademark Office on Jan. 19, 2012 for U.S. Appl. No. 29/411,291, filed Jan. 19, 2012 (First Named Inventor—Dunn) (7 pages).
Specification, Claims, and Drawings entered by the U.S. Patent and Trademark Office on Jan. 19, 2012 for U.S. Appl. No. 29/411,293, filed Jan. 19, 2012 (First Named Inventor—Dunn) (7 pages).
Specification, Claims, and Drawings entered by the U.S. Patent and Trademark Office on Jan. 19, 2012 for U.S. Appl. No. 29/411,295, filed Jan. 19, 2012 (First Named Inventor—Dunn) (7 pages).
Notice of Allowance entered by the U.S. Patent and Trademark Office on Apr. 4, 2012 for U.S. Appl. No. 29/411,295, filed Jan. 19, 2012 (First Named Inventor—Dunn) (7 pages).
Specification, Claims, and Drawings entered by the U.S. Patent and Trademark Office on Jan. 19, 2012 for U.S. Appl. No. 29/411,296, filed Jan. 19, 2012 (First Named Inventor—Dunn) (7 pages).
Specification, Claims, and Drawings entered by the U.S. Patent and Trademark Office on Jan. 19, 2012 for U.S. Appl. No. 29/411,297, filed Jan. 19, 2012 (First Named Inventor—Dunn) (7 pages).
Specification, Claims, and Drawings entered by the U.S. Patent and Trademark Office on Jan. 19, 2012 for U.S. Appl. No. 29/411,298, filed Jan. 19, 2012 (First Named Inventor—Dunn) (7 pages).
Specification, Claims, and Drawings entered by the U.S. Patent and Trademark Office on Jan. 19, 2012 for U.S. Appl. No. 29/411,300, filed Jan. 19, 2012 (First Named Inventor—Dunn) (8 pages).
Specification, Claims, and Drawings entered by the U.S. Patent and Trademark Office on Jan. 19, 2012 for U.S. Appl. No. 29/411,309, filed Jan. 19, 2012 (First Named Inventor—Dunn) (8 pages).
Specification, Claims, and Drawings entered by the U.S. Patent and Trademark Office on Jan. 19, 2012 for U.S. Appl. No. 29/411,311, filed Jan. 19, 2012 (First Named Inventor—Dunn) (8 pages).
Specification, Claims, and Drawings entered by the U.S. Patent and Trademark Office on Jan. 19, 2012 for U.S. Appl. No. 29/411,313, filed Jan. 19, 2012 (First Named Inventor—Dunn) (8 pages).
Specification, Claims, and Drawings entered by the U.S. Patent and Trademark Office on Jan. 19, 2012 for U.S. Appl. No. 29/411,315, filed Jan. 19, 2012 (First Named Inventor—Dunn) (8 pages).
